UNITED STATES PATENT OFFICE.

JAMES M. JAY, OF NEW YORK, N. Y., ASSIGNOR TO HIMSELF AND GEORGE LESTER, OF SAME PLACE.

IMPROVEMENT IN MACHINES FOR CUTTING SHEET METAL.

Specification forming part of Letters Patent No. 172,879, dated February 1, 1876; application filed December 22, 1875.

To all whom it may concern:

Be it known that I, JAMES M. JAY, of the city, county, and State of New York, have invented a new and useful Improvement in Machinery for Cutting Thin Metal into Narrow Strips, of which the following is a specification, reference being had to the accompanying drawings forming part of the same.

My invention relates to a machine designed to cut thin metal sheets into long narrow strips or ribbons; and consists of the combination of devices for the purpose hereinafter particularly described.

Figure 1 is an elevation of a machine containing my improvements, presenting a rear view of the machine. Fig. 2 is a plan, Fig. 3 a front elevation, and Fig. 4 a side elevation, of the same.

A is a frame or hollow pillar, upon which the moving parts of my machine are mounted. B B' are revolving shear-cutters, mounted on shafts a a, which have their bearings in the head-block C, secured upon the top of the pillar A. b b' are spur-gears on the said shafts, whereby the latter are geared to run together. D is a spool or reel formed of two disks fixed on a shaft, which has its bearings in a bracket, E, secured upon the head-block C. F is the driving-pulley, fixed on the shaft a; and F', a loose pulley. G G' are rods designed to support the metal and present it to the cutters. They are fixed in brackets e e' e'' e''', secured upon the head-blocks. These rods are hollow and provided with slotted openings d d', extending from their outer ends to the brackets e e'', respectively. H H' are pressure-guides, each having a short shaft or stem extending through the slots d d', respectively, into the hollow rods G G'. To the stems of these guides are attached cords, which run through the rods and over pulleys e e' at the rear ends of the rods, with weights f f' attached to their ends, whereby the guides are pressed against the outer edge of the metal while the latter is being cut, thus forcing the metal against the gage g. In place of the cord and weights, springs may be used. The gage g is secured to and made adjustable on a bar, k, by screw-bolts n n', which are fastened to the said gage and pass through holes in said bar, with nuts on either side of it. j is a hinged guide, forked at its outer end to embrace the bobbin or reel D near its perimeter, and fur-

nished with set-screws l l' to adjust the guide accurately to the reel. It is hinged, as shown in Fig. 2, in order that it may be thrown up out of the way when the reel is to be removed from its shaft. Motion is given to the reel or bobbin D from the shaft of the cutter B by a band, s, running from a pulley, p, on the latter to a pulley, q, on the shaft of the reel.

The sheet of metal intended to be cut into a continuous strip or ribbon is bent into the form of a cylinder, and its opposing edges soldered together, so as to form a large tube. This tube is placed upon the rods G G', as seen in Fig. 1, the pressure-guides H H' pressing against its outer edge, forcing the opposite edge against the gage g; a cut being made into the inner edge of this cylinder, and the strip thus severed passed by the cutters and wound around the spool, the machine is ready for operation. Then, when motion is communicated to the driving-pulley, it is evident that a continuous strip or ribbon will be cut spirally around the cylinder until the whole is cut up and wound upon the spool D. When a spool is filled it may be removed, an empty one put in its place, and the operation continued.

This machine is specially designed to cut up zinc sheets into strips to be used in making glazier-tacks in a machine for which an application for patent was filed by me March 9, 1875, and passed for issue June 22, 1875.

What I claim as my invention, and desire to secure by Letters Patent, is—

1. A machine for cutting sheet metal into strips, wherein are combined the cutters B B', the rods G G', and the pressure-guides H H', one or more, constructed to operate as and for the purpose described.

2. The combination, in a machine for cutting sheet-metal into strips, of the spool D and the hinged guides j, as and for the purpose specified.

3. The combination, in a machine for cutting sheet metal into strips, of the pressure-guides H H' and the spool D, as and for the purpose specified.

Witness my hand, this 20th day of December, 1875.

JAMES M. JAY.
